UNITED STATES PATENT OFFICE.

CARL H. MILLER, OF CLEVELAND, OHIO.

COMBINED SOLID-FUEL AND GAS RANGE.

1,090,163.

Specification of Letters Patent. Patented Mar. 17, 1914.

Application filed November 20, 1911. Serial No. 661,273.

To all whom it may concern:

Be it known that I, CARL H. MILLER, citizen of the United States, residing at Cleveland, in the county of Cuyahoga and State of Ohio, have invented certain new and useful Improvements in Combined Solid-Fuel and Gas Ranges, of which the following is a specification.

This invention relates to a combined solid fuel and gas range, and the invention consists in the construction and combination of parts, substantially as shown and described and particularly pointed out in the claim.

In the accompanying drawings, Figure 1 is a horizontal sectional view of the stove, and Fig. 2 is a vertical sectional view thereof. Fig. 3 is a cross section, front to rear, and Fig. 4 is a side elevation enlarged of the gas supply pipe and draft damper for the oven. Fig. 5 is a sectional elevation of said parts at right angles to Fig. 4 and vertically across the said damper.

As thus shown the invention comprises several new and important features, as will hereinafter fully appear and consists, first, in means for controlling the exhaust passage for the products of combustion from an oven in which a gas burner is employed. Obviously it is important for a healthful and successful operation of an oven having the products of combustion discharged therein that there should be a free outlet or exhaust for such products, and yet in gas stoves of this kind with exhaust dampers duly provided it is every day experience that the said dampers are neglected and allowed to remain closed when the gas is turned on and the oven is expected to do its work in the appointed way.

The trouble heretofore has been that the said dampers were separate and independent parts which were intended to be closed when fuel was burned in the fire pot and to be opened when gas was used to heat the oven or for broiling in the upper portion of the oven, but the trouble was that the said dampers were liable to be forgotten in both cases and the results were especially bad in the case of gas if the dampers were left closed, as when using wood or coal. Now, in order to remedy this objection I have provided a rotatable or plug valve *v* in the feed pipe 2 for the oven burner *b* and the broiler burner *b'* with an operating connection between said valve and the exhaust damper *d* from the oven and which opens into the exhaust or draft passage or space 3

of the range. These connections and parts are shown enlarged in Figs. 4 and 5, and the relation thereof to or in the range in Figs. 1 and 2. The distributing pipe 4 along the front and side of the range and the pipe 2 therefrom are a common arrangement, and the valve or valve plug *v* is shown as having a handle 5 and the damper *d* has a stem 6 fixed centrally therein and slidably supported at its inner end in a bearing 7 and connected at its outer end with the said handle 5 by screw or pin 8. The said pin or screw engages through a slot 9 in the end of said stem and a spiral spring 10 about said stem and between a collar thereon and said handle serves to exert a normal inward pressure upon the damper and hold it upon its seat *s*. This construction provides for always opening and closing the damper automatically when the valve is opened and closed and insures absolute safety in the use of gas interchangeably with solid fuel. When the valve *v* is closed the damper *d* is closed also both by means of the valve handle and the spring, and when the said valve is open, whether purposely or by neglect, the damper *d* is open also and the danger which otherwise would attend a tightly closed oven flooded with gas or the products of combustion, is prevented. A suitable annular hood *h* provides a seat for damper *d*.

Respecting the safety feature of damper *d* connected with valve *v* it may be added that the immediate necessity for this connection lies in the extreme danger of gas explosions in the stove if no such connection be provided. For example, suppose the said valve to be opened and the damper to be closed; when the oven burner is lighted it will soon become chocked for want of oxygen and go out but the gas will continue to flow meantime and will either escape through a leak and light back or possibly ignite from one of the top burners when the oven door is opened. Both these contingencies have been actual experiences, and the danger from this source evidently is most serious and should not be possible. Nor is it possible with my present safety connections between the said valve *v* and the draft damper *d*, as described.

What I claim is:

A kitchen range having an exhaust flue for the products of combustion and an oven provided with an exhaust passage at its top into said flue, in combination with a gas supply pipe at the front of the range and a

gas burner in said oven having supply connection with said pipe, a hood over the entrance to said exhaust passage and a damper fitted to the outside of said hood, a valve adapted to control the flow of gas to said oven burner having a depending handle, a rod loosely connected with said handle at one end and a support for the other end thereof in said hood and having said dam-

per mounted thereon and a spring on said rod adapted to force said damper to its seat on said hood.

In testimony whereof I affix my signature in presence of two witnesses.

CARL H. MILLER.
